(57) **CLAIM**

The ornamental design for a vertical utensil rest, as shown and described.

DESCRIPTION

The invention is a device for resting a spoon, stirrer or other cooking wares in an upright orientation so as not to stain the counter top and to occupy minimal space.

FIG. 1 is a front perspective view of the vertical utensil rest showing my new design;

FIG. 2 is a front elevation view thereof;

FIG. 3 is a rear elevation view thereof;

FIG. 4 is a right side elevation view thereof and it is a mirror image of the left side elevation view;

FIG. 5 is a top plan view thereof; and,

FIG. 6 is a bottom plan view thereof.
